(No Model.)

A. P. DE VOURSNEY.

LAMP AND CHANDELIER.

No. 257,478.

Patented May 9, 1882.

Fig. 1

UNITED STATES PATENT OFFICE.

ABRAHAM P. DE VOURSNEY, OF MONTCLAIR, NEW JERSEY.

LAMP AND CHANDELIER.

SPECIFICATION forming part of Letters Patent No. 257,478, dated May 9, 1882.

Application filed September 30, 1881. (No model.)

To all whom it may concern:

Be it known that I, ABRAHAM P. DE VOURSNEY, a citizen of the United States, residing in Montclair, Essex county, New Jersey, have 5 invented certain Improvements in Lamps and Chandeliars, of which the following is a specification.

This invention relates to that class of lamps in which an elevated reservoir to contain the oil 10 is employed in connection with a float-valve to regulate the admission of the oil to the burner; and it consists partly in the construction and arrangement of the elevated reservoir and the reflector, partly in the construction and ar- 15 rangement of the valve, and partly in the combination of the various parts, all as will be more particularly hereinafter set forth, and defined in the claims.

In the drawings which serve to illustrate 20 my invention, Figure 1 is a sectional elevation of the lamp; and Fig. 2 is a sectional view of the valve-seat, drawn to a larger scale than Fig. 1.

A is a conical reflector with a central aperture for the passage of the chimney B.

C is the oil-reservoir, which is in the nature of a tubular ring or annulus, made by preference to fit into an angle formed by the reflector and a raised rim or flange, a, on the same. 30 To avoid as far as possible the transmission of heat from the reflector to the reservoir, I prefer to support the latter on two or more raised ribs or projections, b b, on the reflector, as shown.

35 Two or more pendent arms, cc', extend from the reflector down to the outer shell or jacket, D, of the oil-well D' of the lamp, on which is mounted in the usual way any good form of burner, E. I have shown an ordinary Argand 40 burner provided with the usual chimney and a flat wick, d; but any suitable form of burner may be employed.

Inside of the oil-well is fixed a tubular float-guide and wick-guard, e, preferably made from 45 some foraminous material, so as to permit the oil to find the same level within it as without. This guide is preferably cylindrical, as is also the jacket D and well D', and said guide is ar- 50 ranged and secured about in the axis of the well, and is provided with a pointed or conical top, f. The oil-well has a tight bottom, g, and

is screwed down into or upon an oil-supply chamber, F, the joint being packed tightly by means of a soft washer, h.

From the reservoir C an oil-supply pipe, i, 55 extends down through the hollow of the pendent arm e, thence through the annular space between the jacket D and the well D', and thence through the bottom g into the chamber F. The flow of oil from the reservoir to the 60 chamber F may be cut off or regulated by a suitable cock, j.

Fixed tightly in the bottom g of the oil-well is a valve-seat, k, the axis of which is vertical. This seat has a longitudinal conical bore, into 65 which is fitted by grinding a conical plug-valve, l, arranged point upward. This valve is connected at its upper end with a hollow float, G, arranged within the float-guide e. The float is guided in its movements up and down in 70 part by the walls of the tube e, and in part by a pin, m, on its upper end, which passes through a hole in a cross-bar in the cap f. When the oil flows into the chamber F from the reservoir it rises through the valve-aperture and to 75 a predetermined height in the oil-well, when the float G will be lifted by its own buoyancy and draw the valve l up to its seat, thus cutting off the influx of oil. As the oil is consumed the float and valve fall and allow the 80 oil to again flow in.

The wick d of the lamp, directed by the conical cap f, passes down into the annular space around the tube e, and is prevented by the latter from interfering with the float G. The 85 valve is coupled loosely to the float to avoid friction in the movements, and the valve is or may be provided with adjustable and remov- 90 able weights n, to insure against its sticking fast to its seat. The weight is made adjusta- 95 ble, so that no more than is necessary may be employed. The float should have buoyancy enough to properly seat the valve, but not enough to draw it too strongly up into its seat.

The chamber F is made readily removable, 95 so that the valve may be got at and cleaned and adjusted with facility.

I find in practice that the heat from the burner is liable to communicate itself to the oil-well, and also to the reservoir, through the 100 reflector or shade, and this is apt to generate vapors in the oil-well, which create a pressure

therein and depress the float, thus seriously deranging the operation of the lamp. To avoid this I mount the reservoir, as before stated, on interposed slender projections, either secured 5 to the reservoir itself, to the reflector, or to neither, but simply interposed; and I provide the oil-well with an outer shell or jacket, D, before described, whereby an air-space is formed around the well, and perforate this outer shell 10 or jacket at o o, near its top and bottom, whereby a circulation of air is maintained around the said well at all times. The reflector also has perforations or apertures o' o', to permit air to pass upward around the reservoir C and 15 protect it against radiated heat.

The pipe i may or may not pass through the arm c and shell D. I employ this construction in deference to appearances and for convenience only.

20 The reservoir C may be of any size required, and the lamp may be suspended from above by means of cords or chains p p. The reflector A may also be of any suitable size, and be more or less coned, as desired or according to 25 the circumstances of the case. Indeed, it might be flat, so as to reflect the rays downward, and it may be plain, corrugated, or constructed in any way common in reflectors.

In lieu of admitting the oil first to the chamber F and then to the valve, it may be admitted directly to the valve by carrying the pipe i to the valve-seat, and arranging it to tap the same at the side. In this construction it would be necessary to open communication between 35 the chamber F and the oil-well.

I am aware that oil-reservoirs have been mounted on and insulated from reflectors of street-lamps, and that annular air chambers or 40 passages have been arranged around the oil-wells of lamps, and I make no claim to these broadly; nor do I claim broadly the employment of a float and valve to regulate the admission of oil to the oil-well, said float being protected by a perforated guard, as these are 45 not new. I am not aware, however, that an

elongated tubular valve-seat, like that herein shown, and a guide and guard for the float, constructed as herein shown, have ever before been employed. Therefore

I claim as new—

1. The combination, with the reflector provided with a flange, a, having perforations o', of the annular reservoir mounted on the reflector, as shown, and insulated therefrom by suitable interposed ribs or projections, as set 55 forth.

2. The combination of the elongated valve-seat, the elongated plug-valve arranged to fit the same, the adjustable weights n, the perforated or apertured guide e for the float, and 60 the float G, linked loosely to the valve and arranged to be guided in its vertical movement, substantially as set forth.

3. The combination of the reflector, the reservoir, the arms c c', the oil-pipe i, arranged 65 in the arm c, the cock j, oil-well D', jacket D, and receiving-chamber F, the jacket D being screwed into said chamber F, and all arranged substantially as shown.

4. The combination of the oil-well, the perforated jacket, the burner, the oil-receiver secured removably to the jacket, the elongated valve and seat, the float, and the foraminous float guide and guard arranged within the well, all arranged substantially as set forth. 70

75 5. The combination of the reflector, the annular reservoir mounted on and insulated therefrom, the arms or supports c c', the oil-pipe i, the burner, the oil-well, the perforated jacket, the oil-receiver and float, the float guide and 80 guard, and the elongated valve-seat and valve, all arranged to operate substantially as set forth.

In witness whereof I have hereunto signed my name in the presence of two subscribing 85 witnesses.

ABRAHAM P. DE VOURSNEY.
